UNITED STATES PATENT OFFICE.

FRANK C. SOPER, OF CHICAGO, ILLINOIS, ASSIGNOR TO THE LUXFER PRISM PATENTS COMPANY, OF WEST VIRGINIA.

DESIGN FOR A PRISM-TILE.

SPECIFICATION forming part of Design No. 26,865, dated April 6, 1897.

Application filed February 9, 1897. Serial No. 622,667. Term of patent 14 years.

To all whom it may concern:

Be it known that I, FRANK C. SOPER, a citizen of the United States, residing at Chicago, in the county of Cook and State of Illinois, 5 have invented a certain new and useful Design for Ornamental Prism-Tiles, of which the following is a description.

My invention relates to a new design for ornamental prism-tiles illustrated in the accompanying drawings, wherein—

Figure 1 is a perspective view of a prism-tile embodying my design. Fig. 2 is a section.

Like letters refer to like parts throughout both figures.

15 The prism-tile consists of the body portion A, provided with the projecting part B. The

sides C of the projection B are ridged, corrugated, or provided with prisms, as shown, and are preferably inclined with relation to each other, the projection B being wider at the 20 lower than at the upper end.

The essential feature of my design is the projecting part B, having the prism-covered sides C, inclined with relation to each other.

I claim—

25 The design for an ornamental prism-tile comprising a projecting portion with inclined prism-covered sides as shown.

FRANK C. SOPER.
